UNITED STATES PATENT OFFICE.

TONY HOFF, LANDON CARROLL SHELTON, AND ALEXANDER MACMILLAN, OF BUTTE, MONTANA.

RIVETING TOOL.

Application filed April 14, 1922. Serial No. 552,647.

To all whom it may concern:

Be it known that we, TONY HOFF, LANDON C. SHELTON, and ALEXANDER MACMILLAN, citizens of the United States, residing at Butte, in the county of Silver Bow and State of Montana, have invented new and useful Improvements in Riveting Tools, of which the following is a specification.

This invention relates to improvements in riveting tools, the general object of the invention being to provide a tool which is formed of several parts so arranged that the outer parts will take the shock of the blow so that the head of the tool will remain on the rivet. Thus the tool is in position ready for the next blow and no time is lost in replacing the tool.

Another object of the invention is to make the head of the tool detachable and to provide different sizes of heads so that the tool can be used in connection with different sizes of rivets.

This invention also consists in certain other features of construction and in the combination and arrangement of the several parts, to be hereinafter fully described, illustrated in the accompanying drawings and specifically pointed out in the appended claim.

30 In describing the invention in detail, reference will be had to the accompanying drawings wherein like characters denote like or corresponding parts throughout the several views, and in which:—

35 Figure 1 is an elevation of the invention. Figure 2 is a longitudinal sectional view. Figure 3 is a view of the head 5.

Figure 4 is a transverse sectional view. In these views 1 indicates the body of the

40 tool which is provided with enlarged ends and a reduced center to form a handle. This body is solid at one end and has a socket 2 which passes through its other end. The face of the solid end is provided with

45 an under cut groove 3 to receive a tongue 4 on the head 5. This head is of tapered shape, as shown, and is provided with an indentation 6 for receiving the bottom of the rivet. The inner end of the head is pro-

50 vided with a screw threaded socket 7 for receiving the screw threaded end of a rod 8, said rod passing through an opening made in the solid part of the body and which opens out into the socket 2. This rod

55 8 is of greater length than the body and it

is provided with a reduced part 10 adjacent its outer end. An absorber block 11 is threaded over the rod 8 and rests in the socket 2 of the body with one end engaging the bottom of the socket. The corners of this block are beveled, as shown, if desired several of these blocks may be used. A bar 12 has a bore 13 in one end for receiving the rod 8 and said bar is slidingly secured to said rod by means of a pin 14 which passes through a hole in the bar 12 and passes through the annular space formed by the reduced part 10 of the rod 8 and bore 13. This arrangement of parts permits the bar 12 to have rotary movement on the rod as well as a limited sliding movement. This bar 12 has a part fitting in the socket 2 so that one end will bear against the block 11, said end being beveled, as shown. The outer end of the bar 12 is enlarged and rounded to fit the palm of the hand, as shown at 15.

The parts are assembled by sliding the tongue of the head in the groove 3 of the body and then passing the rod 8 through the hole and steering it into the socket 7. This will secure the head to the body. The block 11 is then placed over the rod and then the bar 12 is put in place and fastened by the pin 14 which may be screw threaded to engage the screw threaded hole in the bar 12. The body is held in one hand with the indentation 6 in the head 5 against the bottom of the rivet and the bar 12 has its end held in the palm of the other hand. The shock of the blows on the rivets will be taken by this bar 12 and the block 11 which are movably attached to the body. Thus the head will remain on the rivet so that no time is lost in replacing the head and preventing improper riveting by the block not being in the proper place. By making the head detachable different sizes of heads may be used with the tool to suit the different kinds of rivets. The block 11 is preferably formed of case hardened steel and as before stated several of these blocks may be used. By beveling their edges sharp corners are avoided which would interfere with the proper working of the device.

It is thought from the foregoing description that the advantages and novel features of the invention will be readily apparent.

We desire it to be understood that we may make changes in the construction and in the

combination and arrangement of the several parts, provided that such changes fall within the scope of the appended claim.

What we claim is:—

- 5 A tool of the class described comprising a body, a riveting head detachably connected therewith, a block movably mounted in the body, a handle slidably connected with the body and engaging the block and a rod hav-

ing screw threaded connection with the head 10 and passing through the body and upon which the block and handle are placed.

In testimony whereof we affix our signatures.

TONY HOFF.

LANDON CARROLL SHELTON.

ALEXANDER MACMILLAN.
